UNITED STATES PATENT OFFICE.

WALLACE E. PINNEY AND THOMAS DONAHUE, OF PROVIDENCE, RHODE ISLAND.

SHADE AND CURTAIN HANGER.

Application filed May 16, 1922. Serial No. 561,327.

To all whom it may concern:

Be it known that we, WALLACE E. PINNEY and THOMAS DONAHUE, citizens of the United States, residing at Providence, in the county of Providence and State of Rhode Island, have invented new and useful Improvements in Shade and Curtain Hangers, of which the following is a specification.

10 This invention relates to certain new and useful improvements in shade and curtain hangers, and the primary object thereof is to provide a device of this type which has spring means for holding the same in position on the window frame, which means is adjustable to not only provide for securement of the device to window frames of varying widths, but to also enable adjustment of the tension of the spring means to 15 thereby obtain effective securement of the device to the window frame.

A further object of the invention is to provide a hanger which has novel means for securing the supporting rods of the inner 25 and outer curtains or overdraperies, as the latter are commonly styled, in position and for enabling adjustment of the rods of the inner curtains.

The invention still further aims to provide means of a novel nature for supporting the shade roll and for also affording a 30 selective means of support for the rods of the overdraperies.

The invention aims to provide a hanger 35 possessed of all of the foregoing features which is of simple and economical construction and which is of easy operation and securement to the window frame, so as to avoid the use of driven fastenings in securing the device in position and the tedious 40 and awkward manipulation of such driven fastenings.

In the drawings:—

Figure 1 is a front elevation of the invention;

Figure 2 is a detail perspective view of one end of the hanger, and

Figure 3 is a longitudinal detail sectional view of the adjustable spring end supporting means.

In proceeding in accordance with the present invention a pair of opposed substantially L-shaped end members are employed which may be formed of rods and which 55 have their horizontal arms 1 arranged at the top of the window frame and their

vertical arms 2 disposed opposite to the side edges of the frame. Spurs 3 are carried by the arms 2 and are adapted to engage or be embedded in the frame. The 60 lower ends of the arms 2 are turned outwardly at right angles as indicated at 4 and are perforated to receive the stems 5 of the substantially L-shaped shade supports 6, screws 4' driven through the ends 65 of the parts 4, holding the stems in adjustable position.

The arms 1 are perforated to receive rods 7, the latter being suitably rigidly secured to the arms 1 and being encircled by the 70 ends of a tensioning coil spring 8, the extremities of the spring being secured about the shanks of screws 9 which latter are carried by adjustable sleeves 10 slidably mounted on the rods 7. The screws impinge 75 against the rods 7 and thereby hold the sleeves 10 and the spring ends in adjusted position of the parts. In this manner, the end members can be adjusted to accommodate window frames of varying widths, and 80 the tension of the spring likewise adjusted to provide for the required spring tension.

Curtain rod supporting arms 11 are provided and are secured at their inner ends in sockets provided therefor in the arms 2 of 85 the end members of the device, being removably secured in place by the screws 12. L-shaped supports 13 for the rods of the inner curtains have reduced arms 14 passed through holes in the arms 11 and secured by 90 screws 15.

Arms 11 are also provided with L-shaped members 16 equipped with screws 17 and the supports 18 are likewise equipped with screws 19. The screws 17 and 19 are employed to clamp the curtain holding rods having semicircular ends to the members 11 and 13 respectively.

A pin 20 is screwed into each of the arms 2 and in cases where rods with perforated 100 ends are employed, the pins 20 are removed from the arms 2 and screwed into holes 21 in members 11.

As shown in Figure 2 the sleeves 10 have flat bottom faces 10' so as to firmly seat on 105 the top edge of the window frame in order to prevent turning of the sleeves during manipulation of the screws 9.

Having thus described our invention, what we claim as new and desire to secure 110 by Letters Patent is:—

1. In a shade and curtain hanger, a pair

2. of L-shaped end members, rods extending outwardly from the horizontal upper ends of the members and with said upper ends disposed across the top part of the window frame, sleeves slidable on the rods, screws carried by the sleeves for adjustably securing the latter to the rods, a coil spring connecting and encircling the rod ends at its ends and having its extremities secured to the shanks of the screws, shade and curtain supports carried by the vertical arms of the end members and prongs on the vertical arms to bite into the vertical edges of the window frame.
15. 2. In a shade and curtain hanger, a pair of end members having parts extending horizontally of and at the top of the window frame, sleeves adjustable on said parts, a coil spring connection encircling said parts at its end portions, screws for securing the sleeves to the said parts, the extremities of the springs being secured to the screws, and shade and curtain supports on the end members.
20. 3. In a shade and curtain hanger, end members, means to secure the members in

position on a window frame, a horizontal arm extending outwardly from each of the members, an L-shaped member on each arm having one end extending through and adjustably secured to the arm, a screw carrier for each arm and for the opposite end of each L-member, and screws on the carriers for engaging curtain rods and for clamping the latter between the screws and onto the arms and onto said opposite ends of the L-members.

4. In a curtain hanger, end members, horizontal rod supports carried by the end members and having vertical threaded sockets, and pins carried by the end members and removable therefrom to engage in the sockets for engagement in the perforations of the curtain rods.

In testimony whereof we have signed our names to this specification in the presence of two subscribing witnesses.

WALLACE E. PINNEY.
THOMAS DONAHUE.
